CLAIM

The ornamental design for a bowl, as shown and described.

DESCRIPTION

FIG. 1 is a right side elevational view of bowl showing my new invention, whereas the left side, front and rear elevational view are identical;

FIG. 2 is a top plan view thereof;

FIG. 3 is a bottom plan view thereof; and,

FIG. 4 is a top, front and right side perspective view thereof. The broken lines shown in the drawings are for illustrative purposes only and form no part of the claimed design.
